UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

FILLED-BAG-SEWING MACHINE.

1,235,846.

Specification of Letters Patent. Patented Aug. 7, 1917.

Application filed June 4, 1912. Serial No. 701,519.

To all whom it may concern:

Be it known that I, DUDLEY S. SEYMOUR, a citizen of the United States, residing at Oak Park, in the county of Cook, State of Illinois, have invented certain new and useful Improvements in Filled-Bag-Sewing Machines, of which the following is a description, reference being had to the accompanying drawing and to the figures of reference marked thereon.

My invention relates to new and useful improvements in machines for sewing filled sacks, and more especially to devices of this character in which the sack is brought by a conveyer to the stitching mechanism and fed past such stitching mechanism. It is desirable in this class of apparatus that the conveyer be driven independently of the sewing mechanism, the former carrying the sack to a point adjacent the stitching mechanism before the latter is set in operation.

It is desirable also in machines of this character, that the operator should have both hands free to properly place the sack with its mouth so as to be fed to the stitching mechanism, and also that the conveyer and stitching mechanisms should be under ready and simple control by the foot of the operator, and to lessen his work, that the conveyer and stitching mechanism should be successively set into operation by substantially one movement on his part.

An object, therefore, of the present invention is to provide means for controlling successively by a single lever, the clutches which operate the vertical operating conveyer shaft, and the vertical operating stitching mechanism shaft, on an organized filled bag apparatus.

A further object is to provide two independent driving connections for the sewing mechanism and conveyer respectively, which driving connections include separate clutches, and a common controlling mechanism for the two clutches, so constructed that one may operate in advance of the other.

These and other objects will in part be obvious and will in part be hereinafter more fully described.

The invention is illustrated in the accompanying drawings, in which,

Figure 1 is a front elevation of a filled

bag sewing apparatus showing my invention applied thereto;

Fig. 2 is an enlarged sectional view, showing the dual drive mechanism.

Referring to the assembled machine as shown in Fig. 1, it is of the Union Special type of filled bag sewing apparatus, as shown in general in Patents Nos. 875,314, 875,339, of December 31st, 1907, and shown more specifically as to the adjustable head type in various pending applications filed by me, of which application Serial No. 536,765, filed January 6th, 1910, is an example.

The framework 1, the endless conveyer 2, the sprocket wheel 3, driving the latter, the sewing head-supporting bracket 4, the bracket 5 supporting the conveyer, and the means for raising and lowering the conveyer operated by the crank handle 6, are all of a usual and well known construction. The source of power for operating the mechanism is herein shown as an electric motor 7, from which power is transmitted to a flat pulley 8, loosely mounted on the upright shaft 9, which is suitably connected to the cross shaft which carries the sprocket 3 for operating the conveyer belt. The pulley 8 has an elongated hub 10, and is supported on a ball bearing 11, and, as above stated, is loose on the vertical shaft 9. I call this the conveyer clutch pulley, and it is provided with a friction surface adapted when the pulley is raised through the operation of the swinging lever 13 controlled by treadle 24, to be brought into engagement with a member 14 which I call the conveyer clutch friction, and which is keyed or otherwise fixed to the shaft 9.

When, therefore, the treadle is depressed, the first movement thereof clutches the pulley 8 to the member or pulley clutch 14, and the vertical shaft 9 is, therefore, rotated, thus transmitting movement to the conveyer 2.

Carried by a hub or sleeve 15 journaled in a bearing bracket 16, is a friction clutch member 17. Its hub 15 is fixed to the shaft 9, and has a ball bearing support 18 on the bracket 16.

Above the shaft 9, is a second upright shaft 19 carrying the belt wheel 20, which is connected by a belt 20^a to the driving

shaft of a sewing machine indicated diagrammatically at 20^b in Fig. 1.

On the lower end of this shaft 19 is fixed the clutch member 21, adapted in the raising 5 of the shaft 9 to be engaged by the friction clutch member 17, and thus drive the shaft 19. It will be understood that splines are placed on the shafts whereby the operating device may be moved up and down the sewing 10 head, and conveyer adjusted, as shown in my aforesaid application, No. 536,765.

This engagement of members 17 and 21 takes place when the operator passes the treadle sufficiently to raise the member 14 15 and with it the shaft a sufficient height.

It will be seen, therefore, by this construction that when the operator depresses the treadle, he will first cause the frictional engagement of pulley 8 and conveyer clutch 20 friction 14, thus driving shaft 9, and operating the conveyer to carry the sacks thereon toward the sewing mechanism.

When the sewing mechanism is reached by the bag in its movement, increased pressure on the treadle will cause engagement of members 17 and 21 of the upper clutch mechanism, and thus rotate the upper shaft and drive the sewing mechanism through the belt wheel 20. The movable clutch members 30 return to normal position by gravity. The swinging lever 13 carries a suitable brake shoe, as shown in Fig. 2, which moves into engagement with the friction clutch member 14 when the clutch parts are separated.

While I have shown and described my invention, and primarily have designed it for use in connection with the successive bringing into operation of the conveyer and 40 the sewing mechanism of a filled bag sewing apparatus, it will be understood that so far as the mechanical movements set forth are applicable to other uses, the invention is not limited to this particular type of apparatus.

Having thus described my invention, what I claim as new and desire to secure by Letters Patent, is:—

1. In a filled bag sewing apparatus, sewing mechanism, a conveyer, a driving member, a driven member for the conveyer, a driven member for the sewing mechanism, and a manually operated member and devices actuated thereby for causing the driving member to successively impart motion 50 to the driven member for the conveyer and to the driven member for the sewing mechanism.

2. In a filled bag sewing apparatus, sewing mechanism, a conveyer, a driving member, a vertical driven shaft for the sewing mechanism, a vertical driven shaft for the conveyer, and means for causing the driving member to successively impart motion 60 to the driven shaft for the conveyer, and to the driven shaft for the sewing mechanism.

3. In a filled bag sewing apparatus, sewing mechanism, a conveyer, a driving member, a vertical driven shaft for the sewing mechanism, a vertical driven shaft for the conveyer, means for causing the driving member to engage and operate the driven shaft for the conveyer, and means for raising the said driven shaft to transmit power to the driven shaft for the sewing mechanism.

4. In an apparatus for sewing filled bags including a conveyer and a sewing mechanism, two vertical shafts one for driving the conveyer and the other for driving the sewing mechanism, and a controlling lever, a clutch operated by the controlling lever to drive the conveyer operating shaft, and clutch members between the two shafts brought into effective operation by a further operation of the controlling lever.

5. In an apparatus for sewing filled bags including a conveyer and a sewing mechanism, a vertical conveyer operating shaft having a friction clutch member fixed thereon, a loose clutch pulley thereon, a controlling lever for moving the clutch pulley into operative engagement with the friction clutch member and thereby transmitting motion from the loose pulley to the conveyer shaft, a second friction clutch member on the upper end of the conveyer shaft, a second vertical shaft above the conveyer shaft and having on its lower end a friction clutch member to be engaged by the second friction clutch member on the lower shaft, 100 in the operation of the controlling lever to raise the lower vertical shaft.

6. The herein described dual drive mechanism comprising a lower vertical shaft and an upper vertical shaft, clutch members respectively carried by the upper end of the lower shaft, and the lower end of the upper shaft, a loose driven pulley carried by the lower shaft, a friction clutch member fixed to the lower shaft, and a controlling member adapted in its initial movement to move the loose pulley into engagement with the fixed friction clutch on the lower shaft, thereby rotating the shaft, and the further movement raising the shaft to cause the upper friction member to engage with and transmit power to the upper vertical shaft.

7. In an apparatus for sewing filled sacks, the combination of sewing mechanism, a conveyer, a driven shaft for operating the 120 sewing mechanism, a driven shaft for operating the conveyer, a clutch mechanism between the two driven shafts, a clutch device for operating the first driven shaft, and a controlling lever in the movement of which 125 the first driven shaft is operated to drive the conveyer, and in the further movement of which the clutch between the two shafts is operated to drive the sewing mechanism.

8. In an apparatus for sewing the com- 130

- combination, of sewing mechanism and conveying mechanism, two driven shafts, co-operating clutch members for connecting the shafts, one of said shafts being movable longitudinally for causing said clutch members to be engaged, a second clutch member fixed on said movable shaft, a clutch pulley and a controlling member for engaging the clutch pulley to move it into engagement with said second fixed clutch member and in its further movement to bodily shift the shaft and cause engagement of the respective clutch members between the two shafts.
15. 9. In an apparatus for sewing filled sacks, the combination of sewing mechanism and a conveyer, a driven member for operating the conveyer, a driven member for operating the sewing mechanism, a clutch mechanism between the two driven members, a clutch device for operating the first driven member, and a controlling lever in the movement of which the first driven member is operated to drive the conveyer, and in the further movement of which the clutch between the two driven members is operated to drive the sewing mechanism.
10. In an apparatus for sewing filled sacks, a driven member provided with a clutch, a conveyer operated by said driven member, a controlling lever for operating the clutch to impart motion to said driven member, a second driven member, a sewing member operated by said second driven member, clutch members between the two driven members, the further movement of the controlling lever beyond that necessary to operate the first driven member moving said first driven member with its clutches to cause the clutching of the two driven members.
11. In a filled bag sewing apparatus, a sewing mechanism, and a conveyer, a plurality of vertically arranged shafts for driving said sewing mechanism and conveyer, a device under control of the operator for driving said conveyer, and means under the control of the operator for joining said shafts together whereby they may be operated as a single shaft to simultaneously drive said sewing machine and conveyer.
12. In a filled bag sewing apparatus, a sewing mechanism, a conveyer, a support for the conveyer, and devices for driving the sewing mechanism and conveyer including a plurality of clutches arranged one above the other, driving connections between one of the clutches and the sewing mechanism, and between the other clutch and the conveyer, and a single controlling means for operating first one clutch and then the other.
13. In a filled bag sewing apparatus, a sewing mechanism, a conveyer, a support for the conveyer, and devices for driving the sewing mechanism and conveyer including a plurality of clutches arranged one above the other, driving connections between one of the clutches and the sewing mechanism and between the other clutch and the conveyer, and a single controlling means for operating said clutches in succession, whereby the conveyer may be operated while the sewing mechanism is idle.
14. In a filled bag sewing apparatus, a sewing mechanism, a conveyer, a support for the conveyer, and devices for driving the sewing mechanism and conveyer including a plurality of clutches arranged one above the other, driving connections between one of the clutches and the sewing mechanism, and between the other clutch and the conveyer, said clutches being so constructed as to be normally held open by gravity, and a single controlling means for operating first one clutch and then the other.
15. In a filled bag sewing apparatus, a sewing mechanism, a conveyer, and means for operating said sewing mechanism and conveyer, including a plurality of shafts arranged one above the other, a plurality of clutches, one of which may be operated for connecting the shafts, and the other of which may be operated for driving one of said shafts, devices for connecting one of said shafts to the sewing mechanism, and devices for connecting the other shaft to the conveyer.
16. In a filled bag sewing apparatus, a sewing mechanism, a conveyer, and means for operating said sewing mechanism and conveyer, including a plurality of shafts arranged one above the other, a plurality of clutches, one of which may be operated for connecting the shafts, and the other of which may be operated for driving one of said shafts, devices for connecting one of said shafts to the sewing mechanism, and devices for connecting the other shaft to the conveyer, said clutches being so disposed as to be normally held open by gravity and a single lever for operating both clutches.
17. In a filled bag sewing apparatus, a sewing mechanism and a conveyer, and means for operating said sewing mechanism and conveyer, including a plurality of driving shafts arranged in longitudinal alignment, a clutch comprising clutch members carried by the ends of said shafts, whereby the endwise movement of one shaft will cause the same to be engaged or disengaged with the other shaft, means for connecting one of said shafts to the sewing mechanism, and means for connecting the other shaft to the conveyer, and a clutch controlled mechanism for driving one of said shafts.
18. In a filled bag sewing apparatus, a sewing mechanism, a conveyer, a supporting

framework therefor, a vertically operated shaft carrying a member below the top of said framework for driving said conveyer, a member above the top of said framework for driving said sewing mechanism, both said conveyer and sewing mechanism being adjustable vertically, and means to effect said adjustment, said vertically operated shaft being divided into two sections and

having means under the control of the operator whereby they can be operated singly or together.

In testimony whereof, I affix my signature in the presence of two witnesses.

DUDLEY S. SEYMOUR.
